UNITED STATES PATENT OFFICE.

WELLER R. CRANDALL, OF LEAVENWORTH, KANSAS, ASSIGNOR TO GEORGE R. ADAMS,
OF LOS ANGELES, CALIFORNIA.

COMPOSING STICK.

Application filed March 30, 1923, Serial No. 628,933. Renewed January 18, 1926.

My invention relates to composing sticks for use by job printers, and has for its object the provision of a stick which may be easily and quickly adjusted to permit setting up of lines of any desired length, and also to provide a stick in which the setting up of standard jobs may be facilitated by overcoming the loss of time now occurring in adjusting the stick to the job to be set up. The invention also seeks to provide means whereby the adjustable head may be securely held in a set position and also to provide means whereby the lines may be lengthened slightly so that they will not be apt to fall while being locked upon the press. These several stated objects, and other objects which will incidentally appear, are attained in such a device as is illustrated in the accompanying drawing, and the invention relates in certain novel features which will be particularly pointed out in the appended claims.

In the drawing:

Figure 1 is a plan view of a composing stick embodying my improvements;

Fig. 2 is a section of the adjustable head taken in a plane extending centrally through the head and parallel with the base of the stick, and

Fig. 3 is a transverse section on the line 3—3 of Fig. 1.

The composing stick proper consists of a flat sheet metal base or bottom 1, a rail or side bar 2 extending along one side edge of the bottom, and a fixed head 3 at one end of the same. The side bar and the fixed head are of somewhat heavier material than the bottom and are riveted or otherwise rigidly secured thereto at a right angle to the same and to each other. The side bar or rail 2 has openings 4 formed therethrough, and these openings are spaced apart one-half an em, while at the opposite side edge of the base or bottom 1 on the upper face of the same are marked graduations 5 which are likewise one-half an em apart, and at intervals along the scale thus produced the indicating marks are extended inwardly over the face of the bottom 1, as shown at 6, so as to define the length of lines used on standard jobs.

The adjustable head 7 consists of a block of suitable durable material and comprises a transverse branch 8 having an underlying

hook 9 adapted to engage around the free edge of the base 1 and thereby guide the adjustable head in its movements and also hold it to the base of the stick, as will be readily understood upon reference to Fig. 3. The head also comprises a longitudinally extending branch 10 having a groove 11 in its under side adjacent its edge adapted to fit snugly but slidably over the rail or side bar 2 so as to co-operate with the underlying hook 9 in holding the head in proper position upon the stick. The longitudinally extending branch of the head is constructed with a chamber 12 in which is mounted a lever 13 equipped with teeth or pins 14 at its inner end projecting laterally outwardly so as to engage some of the openings 4. A spring 15 is housed within the head and bears upon the end of the said lever so as to tend constantly to hold the teeth or pins 14 toward the side bar 2 and in engagement with the proper openings 4 therein. At the outer end of the lever 13 is pivotally attached the shank 16 whereby pressure may be exerted upon the lever in opposition to the spring 15 to withdraw the locking pins 14 or teeth 14 from the side bar 2 to permit the head to be adjusted. A thumb piece 17 is provided at the outer end of the shank 16 and is slidably fitted thereto so that it may be set to bear against the branch 10 of the head and thereby lock the latch in engagement with the rail, or may be set in alignment with the shank for releasing the latch. The transverse branch of the head is provided with sockets 18 receiving studs or pins 19 on the inner side of a rest or shim plate 20 which is adapted to bear against the upper face of the bottom 1 of the stick and be held against the ends of the matter set up upon the stick. Extending centrally from the said rest through the head is a screw or threaded stem 21, and upon the outer end of the said screw is a nut 24 bearing against the outer side of the head whereby the rest may be locked in a set position. As shown in the drawing, a space 25 will be produced between the rest 20 and the head, and in this space leads or shims having a thickness equal to one-half an em or a point may be inserted so as to hold the rest firmly against the ends of the matter set up. If the shims be removed, the rest 20 may be withdrawn from the composed matter

without disturbing it so that it may be handled easily and successfully by the lock-up man. It is to be understood that, if preferred, the shim plate may be fitted upon the fixed head 3.

In job printing offices, a large percentage of the work is standard in character, that is to say, the lines of type are of fixed length and ordinarily considerable time is lost in adjusting the composing stick so that the lines will be of the proper length. It will be noted that in my device the lines of graduations, indicated by the reference numeral 6, are extended inwardly beyond the scale 5 and have certain legends displayed in connection therewith so that the adjustable head 7 may be quickly brought to the proper point of the stick to conform to the matter to be set up. When the job is divided among several compositors, the composing sticks may all be set quickly to exactly the same measurements so that the parts of the job may be easily brought together without re-adjustment after they have been set up. To adjust the heads 7 to the desired point of the stick, it is only necessary to exert slight pressure upon the thumb piece 17, thereby withdrawing the locking teeth or pins 14 from the side bar 2 and then push the head to the proper point on the scale 5, whereupon the thumb piece 17 may be released and the spring 15 will at once cause the locking pins or teeth 14 to engage the adjacent openings 4 and hold the head in the set position. A slot 22 is provided between the head 7 and the base 1 of the stick so that in setting up book headings the copy may be slipped through the slot and the type set on top of the copy.

My improved composing stick is exceedingly simple and inexpensive and will be

found highly efficient as a time-saving tool in job-printing offices.

Having thus described the invention, what is claimed as new is:

1. The combination with a composing stick, of a head fitted thereto and having an opening extending therethrough longitudinally of the stick, a rest disposed at the inner side of the head, a threaded stem extending from the rest through the opening in the head, and a nut mounted on the said stem and bearing against the outer side of the head.

2. The combination with a composing stick having a series of openings extending through its side rail, of a head slidably fitted upon the stick, a lever mounted within the head, locking teeth carried by the lever and adapted to engage any of the openings in the side rail of the stick, means bearing upon one end of the lever to hold the locking teeth in engagement with the said openings, and means at the opposite end of the lever operable to release the locking teeth from the openings, said means including a thumb piece shiftable to engage against the side of the head and thereby prevent release of the locking teeth.

3. The combination with a composing stick, of a head constructed at its ends to slidably engage the edge of the bottom of the stick and the side rail of the stick respectively, and means housed within the head to engage the side rail of the stick and lock the head thereto in a set position, a slot being provided between the head and the bottom of the stick to permit copy to be inserted under the head.

In testimony whereof I affix my signature.

WELLER R. CRANDALL. [L.s.]
